UNITED STATES PATENT OFFICE.

GEORG KIRKEGAARD, OF NEW YORK, N. Y., ASSIGNOR TO IMPERIAL STOPPER COMPANY, A CORPORATION OF MAINE.

BOTTLE-STOPPER.

No. 889,137.

Specification of Letters Patent.

Patented May 26, 1908.

Application filed September 10, 1907. Serial No. 392,130.

To all whom it may concern:

Be it known that I, GEORG KIRKEGAARD, a citizen of the United States, residing at the city of New York, in the borough of Brooklyn and State of New York, have invented certain new and useful Improvements in Bottle-Stoppers, of which the following is a full, clear, and exact description.

This invention relates to stoppers for 10 bottles, jars and similar receptacles, and is of that type which comprises a metallic cap with means for engaging an annular shoulder on the exterior of the neck of the bottle to hold under compression a packing disk inter- 15 posed between the mouth of the bottle and the cap.

The object of the invention is to provide 20 means for holding the cap on the bottle against the internal pressure which for its efficiency depends upon the shape or formation of the metallic portion of the cap rather than upon the stiffness or weight of the metal of which the cap is composed; I am thus able to use a comparatively thin metal for the cap 25 and achieve a corresponding economy in the manufacture thereof.

A further object of the invention is to provide 30 a construction which will aid in the removal of the stopper from the bottle.

My improved construction is illustrated in 35 the accompanying drawing, in which

Figure 1 is a side elevation of the cap or stopper before it is applied to the bottle; Fig. 2 is a plan of the same looking at its under side; Fig. 3 is a section on line $x-x$ of Fig. 2; Fig. 4 is a section on the line $y-y$ of Fig. 2; Fig. 5 is a section of the cap applied to the bottle; and Fig. 6 is a side elevation of the stopper showing a removing device.

The cap comprises essentially a disk 1, having 40 integrally formed with it a vertical depending wall 2, and a flaring rim 3, depending from the vertical wall. The cap contains the usual disk of packing material 4, such as 45 cork or paper, which is to be compressed against the mouth of the bottle to effect the seal. This cap is adapted to be applied to the common form of bottle having an exterior annular inwardly inclined shoulder 5, to 50 be engaged by the holding devices on the cap. The said holding devices of my improved cap are formed upon the flaring rim 3. For this purpose the shape of the rim is not flat like a zone from a cone, but is curved like a

zone from a dome. It is provided with a 55 series of inwardly and upwardly bent lips 6, each being formed by bending a short length of the edge of the rim inward and upward, leaving short intermediate portions of the extreme edge unbent, as indicated at 7, into 60 which the bent-up lips merge. The lips are thus reinforced by their connection with the extreme edge of the rim.

When the cap is applied to the bottle, it is forced downward thereon until the cork is 65 compressed so that the upper edge of the lips will fall within the zone of the shoulder 5. Then by forcing the rim 3 inward to the position shown in Fig. 5, the upper edges of the lips will be forced against the shoulder 5 and 70 hold the cap on the bottle with the cork under compression. The strength of this hold is increased from the fact that the lips which rest with their edges against the shoulder 5 taper down into connection with the extreme 75 edge at 7. Thus the lips are prevented from unfolding or bending downward, and the resistance of the cross-section of the metal is obtained to prevent the stopper from becoming forced from the bottle. The ma- 80 chine or tool for applying this cap to the bot- tle will be very simple, since it will require only the plunger to press on the top of the cap and a simple ring passed down on the outside of the vertical wall 2 and forced in- 85 ward on the rim 3 to the position shown in Fig. 5.

In Fig. 6 I have shown an improved form of device for facilitating the removal of the cap from the bottle. Various forms of han- 90 dle have been heretofore proposed which have been in the form of a strip depending from the edge of the cap and intended to be grasped in the hand to lift one side of the stopper and thus free it. But where the 95 stopper is made of very thin or light metal, as is possible in the construction hereinabove described, the simple tail piece is impractical for handling, since it merely bends and does not afford any leverage to free the cap. 100 Therefore I propose providing the tail piece 8, which is made a little wider than usual, with an eye or opening 9, in which any tool, such as a fork, button hook or a nail, can be inserted and used to pull the stopper from 105 the bottle, the thin metal used being amply strong to stand the force necessary to be exerted for this purpose.

Having now described my invention, what I claim, is:—

1. A bottle stopper comprising a metallic cap containing a packing disk and having a depending flange provided with a plurality of inwardly and upwardly turned lips merging at their extremities into the extreme edge of the flange.
2. A bottle stopper comprising a metallic cap having a packing disk therein and having a vertical side wall and a flaring rim or edge

projecting therefrom, said rim or edge having a series of inwardly and upwardly turned lips, the ends of which merge into the extreme edge of the flaring rim, for the purpose 15 set forth.

In witness whereof, I subscribe my signature, in the presence of two witnesses.

GEORG KIRKEGAARD.
